UNITED STATES PATENT OFFICE.

CHARLES S. DUTTON, OF SAN FRANCISCO, AND GEORGE H. DERRICK, OF OAKLAND, CALIFORNIA.

ELECTRICALLY-OPERATED STAMPING DEVICE.

Application filed August 20, 1923. Serial No. 658,415.

To all whom it may concern:

Be it known that we, CHARLES S. DUTTON and GEORGE H. DERRICK, citizens of the United States, and residents, respectively, of San Francisco, county of San Francisco, and Oakland, county of Alameda, State of California, have invented a new and useful Electrically-Operated Stamping Device, of which the following is a specification.

The present invention relates to improvements in electrically operated stamping devices and its particular object is to provide a switch in connection with an electro-magnet having a plunger therein for actuating an object placed in operative relation to the plunger, which allows the object to close the switch by the mere insertion thereof while the action of the plunger removes the object and allows the switch to open automatically. A further object of the invention is to provide a platform constructed to be operated by the plunger of the electro-magnet. Further objects and advantages of our device will appear as the specification proceeds.

The preferred form of our invention is illustrated in the accompanying drawing in which Figure 1 shows a side view of our electro-magnet and the switch arrangement. Figure 2 an enlarged detail view of the operation of the same showing the switch closed by the insertion of the object to be acted on, Figure 3 a similar view representing a later stage in the operation, and Figure 4 a wiring diagram for our device. While we have shown only the preferred form of the invention it should be understood that various changes or modifications may be made within the scope of the claims hereto attached without departing from the spirit of the invention.

The electro-magnet power plant or motive means (1) is mounted on a suitable base (2) and has a plunger (3) movable therein. In the device shown, a second electro-magnet (4) is provided having an armature (6) disposed in front thereof adapted to establish electrical connection between two stationary contact points (7) and (8) when the armature is drawn toward the electro-magnet (4) by the energizing of the latter. The electro-magnet (4) has a switch (9) incorporated therein which latter forms the principal part of the present invention.

The switch (9) comprises a stationary contact (11) disposed in operative relation to a platform (12) which latter has a member (13) depending therefrom extending into the electro-magnet and guided by the same. A second contact member (14) is supported on a vibrating spring (16) and normally occupies a position within a recess (17) in the platform so that the upper portion of the spring (16) extends slightly above the platform when the latter is in its lowermost position. This construction allows the object (18) when brought in operative relation relative to the platform (12) and introduced in the manner illustrated in Figures 1 and 2 to force the contact (14) toward the contact (11) and thereby close the switch (9). The closing of the switch (9) allows the electro-magnet (4) to become energized and to connect the contacts (7) and (8) by means of the armature (6) which latter operation closes the circuit of the electro-magnet (1) so that the latter becomes energized and its plunger (3) is forced upwardly, raising the platform (12). The raising of the platform causes the object (18) to become disengaged from the contact member (14) and the latter is allowed to return, under the influence of the spring (16), to its original position in the manner indicated in Figure 3 whereby the electro-magnet (4) becomes de-energized, which again causes the armature (6) to become disengaged from the two contacts (7) and (8) whereby the circuit of the main electro-magnet (1) is opened. The return of the plunger (3) then allows the platform (12) to return to its original position so that now the contact (14) again projects above the platform and is ready to be actuated by the next object to be acted on.

The electrical connections may be described as follows: The two wires (21) and (22) may be connected to any ordinary lamp socket. When the switch (9) is closed by the insertion of the object (18) the current flows from the wire (22) through the wire (23), the spring (16), the switch (9), the wire (24), the electro-magnet (4), the wire (26) and the wire (21). This current establishes electrical connection between the contacts (7) and (8) by drawing the armature (6) toward the electro-magnet (4) whereby a circuit is closed including the

following elements: The wire (22), the wire (23), the contacts (7) and (8), the wire (27), the windings of the electro-magnet (1), the wire (28) and the wire (21).

5 Our switch at the present time is used in connection with a stamping device and the platform (12) performs the function of forcing the object (18), which may be a strip of paper, a ticket or the like, into contact with the stamping block (29) shown above the platform (12). It should be understood, however, that the switch is considered a device of general application and that we do not desire to in any manner confine our invention to the said stamping device.

The operation of the switch will be readily understood from the foregoing description. The object (18) is placed on the platform (12) and closes by its mere insertion the switch (9) which energizes the electro-magnet (4), connecting the two contacts (7) and (8) and thereby energizing the electro-magnet (1). The plunger (3) rises and forces the platform (12) and the object (18) lying thereon, against the face of the opposing block (29). The rising of the platform causes the object (18) to be disengaged from the contact (14) and the latter is allowed to spring back into a circuit-opening position as indicated in Figure 3, whereby the two electro-magnets become de-energized successively. The plunger (3) thereupon returns to its original position.

35 It will be noted that the contact (14) when the switch is open rests against the rear wall of the recess (17) in the platform (12). This arrangement allows the spring (16) carrying the contact (14) to come to rest immediately after it returns to the recess since the engagement of the spring with the rear wall of the recess tends to deaden any vibration of the spring (16) that might possibly cause a repeated closing of the switch.

We claim:

1. In a device of the character described, a movable platform adapted to slidably support an object to be acted upon, a normally opened spring-controlled switch correlated to the platform and adapted to be disposed in the path of movement of said object to

be acted upon, and a normally de-energized electro-magnet in circuit with such switch, said platform serving to permit the object to be acted upon to close the switch and energize the magnet and then cause the platform to move said object away from the switch and permit the latter to open and again deenergize said magnet. 55

2. In a device of the character described, a normally deenergized electro-magnet having a movable platform and a switch in circuit with said magnet comprising a stationary member in operative proximity to the platform and a spring-actuated movable member interposed between said stationary member and the platform allowing an object to be acted on by the platform to close the switch to energize the magnet and actuate the platform so as to move the object away from the switch while simultaneously permitting the switch to open automatically so as to again deenergize the magnet. 70

3. In a device of the character described, an electro-magnet having a plunger therein, a platform having a member thereon extending into the electro-magnet adapted to be actuated by the plunger when the electro-magnet is energized and an electric element 80 in the circuit of the electro-magnet comprising a stationary member mounted in operative proximity to the electro-magnet and a spring-actuated movable member normally disposed in a recess in the platform allowing an object to be acted on to close the electric element by being brought into operative relation with the platform and allowing the electric element to open when the platform is moved by the action of the plunger. 85

4. In a device of the character described, an opposing surface, a movable element mounted for cooperation therewith in affecting an object inserted between the latter and the surface, electro-magnetic means for operating the movable element and a normally open switch in said means mounted relative to the movable element to allow the object to close the switch by its insertion while the movable element upon becoming active removes the object from its switch closing position and allows the switch to open. 90
